US00D617782S

(12) **United States Design Patent**
Kim

(10) **Patent No.:** US D617,782 S
(45) **Date of Patent:** ** Jun. 15, 2010

(54) **WIRELESS MODEM**

(75) Inventor: **Jin-Young Kim**, Seoul (KR)

(73) Assignee: **Pantech & Curitel Communications, Inc.**, Seoul (KR)

(**) Term: **14 Years**

(21) Appl. No.: **29/333,536**

(22) Filed: **Mar. 11, 2009**

(30) **Foreign Application Priority Data**

Sep. 12, 2008 (KR) 30-2008-039880

(51) **LOC (9) Cl.** 14-03

(52) **U.S. Cl.** D14/242

(58) **Field of Classification Search** D13/133, D13/168; D14/133, 240, 484.1, 480.6, 435.1, D14/358, 374, 242, 480.1, 346, 361-363, D14/365-367, 433, 217, 218, 142; 361/757; 439/131, 159, 501, 528, 623, 652, 654; 379/220.1, 379/25, 93.09, 93.15, 93.14, 156, 424; 451/550.1, 451/557; 324/156

(57) **CLAIM**

The ornamental design for a wireless modem, as shown and described.

DESCRIPTION

FIG. 1 is a perspective view of the wireless modem of the present invention;

FIG. 2 is a front elevation view of the wireless modem shown in FIG. 1;

FIG. 3 is a rear elevation view of the wireless modem shown in FIG. 1;

FIG. 4 is a left side elevation view of the wireless modem shown in FIG. 1;

FIG. 5 is a right side elevation view of the wireless modem shown in FIG. 1;

FIG. 6 is a top plan view of the wireless modem shown in FIG. 1;

FIG. 7 is a bottom plan view of the wireless modem shown in FIG. 1; and,

FIG. 8 is a perspective view of the wireless modem shown in FIG. 1 with the front cover opened and the USB plug rotated.
